UNITED STATES PATENT OFFICE

OSCAR MATHER, OF CHATTANOOGA, TENNESSEE, ASSIGNEE TO AMERICAN HOIST
CORPORATION, OF CHATTANOOGA, TENNESSEE, A CORPORATION OF DELAWARE

LIFTING DEVICE

Application filed September 13, 1928. Serial No. 305,783.

This invention relates to lifting devices and particularly to those devices intended for use in lifting automobiles for the purpose of cleaning, inspection or repair of the under 5 portions thereof.

In the use of automobile lifting devices for use in garages and repair shops it has been found advantageous to lift automobiles in such a way that not only will the under portion be accessible, but that the wheels may turn and be removed if found to be desirable. It has also been found to be desirable to have the lifting means take up as little floor space as possible when the device is not in use.

15 The primary object of this invention is the provision of an improved lifting device for automobiles.

Another object of this invention is the provision of an automobile lifting device which 20 will exert its lifting force in such a way as to leave all of the working parts of the automobile including the wheels, available for inspection, cleaning and repair.

Another object of this invention is the provision of an automobile lifting device which 25 will have its lifting power applied to a single vertical lifting screw and in turn transmitted to a pair of toggle sets to lift the automobile by the combined action of the toggle sets.

30 Other and further objects of my invention will be apparent to one skilled in the art from a reading of the complete specification and claims.

Referring to the drawings wherein is illustrated a preferred embodiment of my invention, Figure 1 is a perspective view of the invention in partially raised position.

Figure 2 is a perspective view of the invention in the lowest position.

40 Figure 3 is a detail sectional view at the base of the lifting screw.

Figure 4 is a detail sectional view through the upright support showing the lifting nut and its connections.

45 Figure 5 is a detail view of the roller connection between the supporting frame and one of the cross members of the lifting device.

Figure 6 is a detail view of the connection at the lower end of one of the cross members 50 of the lifting device.

In the drawings, similar reference characters refer to the same or similar parts throughout the several views of the drawings.

One of the important features of this invention is the compactness of the device when 55 not performing its lifting function.

On the floor or other solid foundation is placed the supporting means which in the embodiment illustrated are the channel beams 10 placed with their flanges upward. 60 These channel beams 10 are placed in parallel relation and at a distance apart substantially equal to the distance between the two longitudinal frame members of the average automobile. These channel beams are secured at 65 one end to another channel member 11. To this latter channel member 11 is secured an upright screw supporting column or frame for the support of the lifting screw to be later described.

This screw supporting frame or column comprises two upright beams as channels 12 having the flanges of each beam, in the embodiment herein illustrated, extending in a direction away from the other beam. This 70 places the webs of each beam toward each other. It is to be noted that these beams are spaced apart to provide a space for the lifting screw and its cooperating nut to be later described. As the lower 75 ends of these channel beams 12 are two spacer brackets 13. At the top of the channel beams 12 is a cap piece 14 which secures the two beams in proper spaced relation to each other at their tops.

Secured at the bottom of the channels 12 and to the channel frame member 11 is a gear casing 15. This gear casing 15 is provided in its bottom with any suitable thrust bearing as the ball thrust bearing 16.

85 Supported by the thrust bearing 16 is the lower end of the screw 17. Above the thrust bearing 16 and keyed to the screw 17 by a key 18 is a worm gear 19. In the side of the worm gear box is mounted a worm 20 which 90 is supported by a motor shaft 21. On the outer end of the motor shaft 21 is located a motor 22 which motor provides power to operate the screw 17 through the shaft 21, worm 20, worm gear 19 and shaft 17.

Having screw threaded engagement with the screw 17 is a nut 22' which nut 22' transmits the lifting force from the screw 17 as will be described. Secured to the nut 22' as by bolts 22^a and on the front of the channel members 12, is a plate 23 to which are secured the lifting braces or hangers 24, 25. The upper hanger or brace 24 is secured on the top of the plate 23 while the lower brace or hanger 25 is secured to the front of the plate 23 by a clamping lug 26^a. The outer ends of both braces 24, 25 are secured to the frame which provides the support for the automobile when the latter is being lifted. This frame comprises side members 26, 27, a front member 28 and a rear member 29. The side members 26, 27 are preferably angle irons and it is at the rear ends of these angle irons that the braces or hangers 24, 25 are secured. To support the frame 26, 27, 28, 29, two sets of lazy tong or parallel motion cross members are provided and are so constructed as to cause the frame to maintain at all times a parallel relation to the support members 10—in other words to remain horizontal regardless of its height. These cross members are each preferably constructed of two channel members 30, 31, pivoted together at 32. In order to reinforce the pivot point and provide a sufficient bearing surface for the pivots 32, blocks 33 have been provided in the space between the flanges of the channel members 30, 31. These blocks fill the space between the channels and are suitably secured in place as by spot welding. These blocks 33 not only provide sufficient bearing surface for the pivots 32, but in addition, they form a reinforcement for the weakest points of the channel members. At the forward ends of the channels 30, 31 are located rollers 30^a, 31^a to contact with and be guided in the under surfaces of the frame members 26, 27 and the upper surfaces of the support members 10, respectively. The rear ends of the channel members 30 are pivoted at 34 to the support members 10 and the rear ends of the channel members 31 are pivoted to the frame members 26, 27, respectively, at 35. The pivot pins 32 are so placed that as the frame 26, 27, 28, 29 is lifted, the rollers 30^a, 31^a will roll on their respective surfaces and lift the forward end of the frame, keeping it at the same level as the rear end of the frame. In operation electric current or other power is supplied to the motor 22. The motor, through the shaft 21, worm 20, and worm gear 19, drives the screw 17. The screw 17 lifts the nut 22' which transmits its lifting force through the plate 23 to the hangers or braces 24, 25 to the frame members 26, 27. As the screw 17 revolves, the frame is lifted. In order to provide a guide for holding the nut steady when the screw is operated, there is provided a guide member 36 which is

bolted to the plate 23. This guide member extends around the flange members of the channel members 12.

It is only necessary to provide this guide member 36 as a steady means for the nut 22' during operation as the frame with its toggle or parallel motion means furnishes its own complete support.

There is provided guide means for the automobile wheels as shown by the frame 37. This guide means centers the frame of the automobile so that the frame 26, 27, 28, 29 will be in proper relation thereto when the lifting operation takes place.

After the automobile is in place, and the power turned on, the lifting operation takes place as already described.

It is to be noted that where an automobile has been raised, the mechanic working on the same may pass freely along between the cross members and below its underside without any interruption by parts of the lifting device.

When it is desired to lower the automobile, the power is reversed in direction by reversing the direction of rotation of the motor 22. This causes the parts to resume their normal or lowered position.

It is to be noted that because the toggle or parallel motion cross members are located between the lifting frame and the support members 10, there is no necessity of having any excavation below the ground level. By this construction the whole lifting device may be shifted to any place and installed without any permanent changes in building construction; yet the lifting device is adapted to be cleared by the lowest of the low-hung automobiles as the latter are driven over the device preparatory to the lifting operation.

While there is shown and illustrated an embodiment of the invention, in detail, it is desired to have it understood that there is no intention to limit the invention and that modifications and changes may be made without departing from the spirit of the invention and within the scope of the appended claims.

Having described my invention what I claim and desire to secure by Letters Patent is:

1. A lifting device for automobiles comprising a flat ground engaging supporting means, a carrying frame having sides to engage the underside of an automobile, parallel motion means for maintaining the carrying frame horizontal when a lifting force is applied at one portion of the frame to raise the same, and raising means connected at one end of the frame, said raising means including an upright screw supporting frame at the end of the carrying frame, a lifting screw supported by the screw supporting frame, a nut on the screw, a vertical tension member connected to the nut, lifting braces connected to

the tension member and to the carrying frame and power means for operating the screw.

2. A lifting device for automobiles comprising a flat ground engaging supporting means, a carrying frame having sides to engage the underside of an automobile, parallel motion means for maintaining the carrying frame horizontal when a lifting force is applied at one portion of the frame to raise the same, and raising means connected at one end of the frame, said raising means including an upright frame at the end of the carrying frame, guides on the upright frame, a screw supported by the frame and parallel with the guides, a nut in cooperative relation with the screw to be lifted thereby and mounted to slide in the guides, a vertical tension member connected to the nut, lifting braces connected to the tension member and to the carrying frame and power means operatively connected to the screw for turning the same.

3. A lifting device for automobiles comprising a supporting means, a carrying frame, a pair of sets of crossed members, the frame being supported by the cross members adjacent their upper ends, the crossed members of each set being pivoted together and proportioned to cause the frame to maintain a substantially horizontal position when raised, the supporting means and carrying frame having means for maintaining corresponding ends of opposite cross members in spaced relation to each other, the corresponding cross members of the sets, except adjacent to their ends, being separated and free of connections to permit free passage of a mechanic therebetween when the lifting device is in use and means for simultaneously raising the frame and operating the cross members to maintain the frame in substantially horizontal position.

4. A lifting device for automobiles comprising a supporting means, a carrying frame, a pair of sets of crossed members, the frame being supported by the cross members adjacent their upper ends, the cross members of each set being pivoted together and proportioned to cause the frame to maintain a substantially horizontal position when raised, the supporting means and carrying frame having means for maintaining corresponding ends of opposite cross members in spaced relation to each other, the cross members of the sets, except adjacent to their ends, being separated and free of connections to permit free passage of a mechanic therebetween when the lifting device is in use, the supporting means extending side-wise to points beyond the centers of wheel support, and means for simultaneously raising the frame and operating the cross members to maintain the frame in substantially horizontal position.

5. A lifting device for automobiles comprising a supporting means, a carrying frame, a pair of sets of crossed members, the frame being supported by the cross members ad-

jacent their upper ends, the cross members of each set being pivoted together and proportioned to cause the frame to maintain a substantially horizontal position when raised, the supporting means and carrying frame having means for maintaining corresponding ends of opposite cross members in spaced relation to each other, the cross members of the sets, except adjacent to their ends, being separated and free of connections to permit free passage of a mechanic therebetween when the lifting device is in use, the width of the carrying frame being less than the distance between the automobile wheels, the frame having spaced side rails to permit access to the underside of the automobile and means for simultaneously raising the frame and operating the cross members to maintain the frame in substantially horizontal position.

6. A lifting device for automobiles comprising a supporting means, a carrying frame, a pair of sets of crossed members, the frame being supported by the cross members adjacent their upper ends, the cross members of each set being pivoted together and proportioned to cause the frame to maintain a substantially horizontal position when raised, the supporting means and carrying frame having means for maintaining corresponding ends of opposite cross members in spaced relation to each other, the corresponding cross members of the sets, except adjacent to their ends, being separated and free of connections to permit free passage of a mechanic therebetween when the lifting device is in use, a mast at one end of the lifting device and a screw means for simultaneously raising the frame and operating the cross members to maintain the frame in substantially horizontal position.

In testimony whereof I hereunto affix my signature.

OSCAR MATHER.
